CLOCKWORK MOVEMENT

Hermann Hausheer, Neuchatel, Switzerland, assignor of one-half to Maurice Jacot-Guillarmod, Neuchatel, Switzerland

Filed Aug. 3, 1964, Ser. No. 386,830

Claims priority, application Switzerland, Aug. 15, 1963, 10,088/63

4 Claims. (Cl. 58—59)

The driving member of time-pieces is generally constituted by a bent coil spring wound round a spindle inside a barrel. The size of said barrel in the plane of the movement is limited by the outer size of the movement and by the presence of the gearwork and of the balance. The elastic limit of the alloy serving for the execution of said springs and also its restricted size prevents such a driving member from storing any large amount of energy.

It has been attempted to replace inside the barrel the bent spring by a torsion spring of a helical shape, but the small size of the barrel has not allowed giving such a driving spring a favorable efficiency.

In other structures, a coil spring is fitted in a groove surrounding them ovement, while the ends of said spring are respectively fitted inside the groove and secured to a lever acting through a catch on the gearwork of the watch. The reduced circular cross-section of the wire serving for the execution of the spring and the very large friction exerted against the wall of the groove have not allowed substituting advantageously such a driving member for the conventional arrangement.

My invention has for its object a watch incorporating a source of energy constituted by a helical spring of the type formed by a blade showing a rectangular cross-section, and the winding axis of which coincides with the axis of the movement. According to my invention, said spring is housed inside an annular rotary barrel located at the periphery of said movement.

I have illustrated by way of example in the accompanying drawing a preferred embodiment of my invention. In said drawings:

FIG. 1 is a diagrammatic front view of the movement, FIG. 2 is a partly sectional side view thereof.

The embodiment illustrated includes a central section containing the gearwork of which the center wheel 1 only is illustrated while the escapement and the spiral balance spring are not illustrated. These different parts are carried inside a cage the periphery of which is provided with an L-shaped groove 2 defined by a flat lateral surface 3 and a cylindrical bottom wall 4.

The driving member is constituted by a helical spring 5 formed by a blade the cross-section of which is rectangular, the longer side of said cross-section being perpendicular to the axis round which the spring is wound. Said spring is carried inside an annular barrel the U-shaped cross-section of which opens outwardly with reference to the side wall of the movement and is coaxial therewith. The upper flange 6 of said barrel is provided inwardly with teeth 7 while its lower flange 8, freely revolvable with reference to the remainder of the barrel, is provided outwardly with teeth 9.

2

The spring 5 is tensioned by rotating the cover to which one end of the spring is secured through the agency of a winding stem and a speed-reducing gear which are not illustrated. The gearwork is driven by the inner teeth 7 formed in the flange 6 of the barrel and a speed increasing gear of which the two gears 10 and 11 are illustrated transmits the energy from said barrel to the center wheel 1 through said gearwork.

The large winding diameter of the spring blade and the torsional stress imparted thereto allow building up round the time piece movement an amount of energy adapted to drive the watch during a long period, or else, if the spring is wound daily, only a very small fraction of its expansion is used, which reduces the modification in torque between the beginning and the end of the unwinding and improves thus the stability of adjustment.

What I claim is:

1. In a time piece the combination of a movement, an annular rotary peripherally recessed barrel extending round the periphery of the movement and a helical blade having a rectangular cross-section wound round the axis of the movement and housed in the peripheral recess of said barrel.
2. In a time piece the combination of a movement, an annular rotary barrel having a U-shaped cross-section opening outwardly and extending round the periphery of the movement and a helical blade having a rectangular cross-section wound round the axis of the movement and housed in the U-shaped periphery of said barrel.
3. In a time piece the combination of a movement, an annular peripherally recessed barrel extending round the periphery of the movement, including two coaxial sections angularly revolvable with reference to each other and of which one is provided with a series of inner teeth coaxial with the barrel, a gearwork controlled by said inner teeth and a helical blade having a rectangular cross-section wound round the axis of the movement and housed in the peripheral recess of said barrel, the ends of said blade being anchored in the corresponding barrel sections.
4. In a time piece the combination of a movement, an annular peripherally recessed barrel extending round the periphery of the movement, including two coaxial sections angularly revolvable with reference to each other and of which one is provided with a series of inner teeth coaxial with the barrel and the other section of which barrel is provided with a series of outer teeth coaxial with the barrel, means engaging said outer teeth to turn the corresponding barrel section with reference to the other, a gearwork controlled by said inner teeth and a helical blade having a rectangular cross-section wound round the axis of the movement and housed in the outer recess of said barrel, the ends of said blade being anchored in the corresponding barrel sections.
